[57] ABSTRACT

A collapsible foot stool including a foot rest having a leg pivotally connected to one extremity thereof and a hook pivotally connected to the opposite extremity thereof. The leg and hook are pivotable between retracted and supporting positions whereby such hook and leg may be pivoted to their retracted positions for storage and may, alternately, be pivoted to respective supporting positions with the leg arranged upright under the foot rest and the free extremity of the hook projecting upwardly to hook over a supporting edge such as the edge of a bathroom fixture.

FIG.2

FIG.5

FIG.4

COLLAPSIBLE FOOT STOOL

BACKGROUND OF THE INVENTION

1. Field of the invention

The present invention relates to a collapsible foot stool which may be conveniently collapsed for storage.

2. Description of the Prior Art:

Prior art foot stools are generally of the rigid type and cannot be collapsed for storage. Further, most prior art foot stools are supported at their opposite extremities by means of ground engaging legs and fail to include hooks for hooking over the edge of a supporting structure.

SUMMARY OF THE INVENTION

The collapsible foot stool of present invention is characterized by a foot rest supported on one end by means of a pivotable leg and on its opposite extremity by means of a pivotable hook which may be hooked over a supporting structure, such leg and hook being pivotable to collapsed positions adjacent the foot rest itself for storage thereof.

The objects and advantages of the present invention will become apparent from a consideration of the following detailed description when taken in conjunction with the accompanying drawing.

DESCRIPTION OF THE DRAWING

FIG. 1 is a perspective view of a foot stool embodying the present invention;

FIG. 2 is a side view of the foot stool shown in FIG. 1 and depicting it in its collapsed position;

FIG. 3 is a side view of the foot stool shown in FIG. 1 and depicting such stool supported on one leg;

FIG. 4 is a top view of the foot stool shown in FIG. 1, and

FIG. 5 is a vertical sectional view taken along the line 5-5 of FIG. 3.

DESCRIPTION OF THE PREFERRED EMBODIMENT

The collapsible foot stool of the present invention includes, generally, a foot rest 11 supported on one end by means of a pivotable leg 13 and on its opposite extremity by means of a pivotable hook 15. Thus, the foot stool may be utilized as shown in FIG. 1 with the collapsible leg 13 in its vertical supporting position and the hook 15 hooked over the rim of a toilet bowl 19 so the user may sit on the toilet seat (not shown) and place his foot on the rest 11 while performing tasks on his shoe or foot. When the foot stool is to be stored, it may then be collapsed to its folded position shown in FIG. 2 for convenient storage.

Referring to FIGS. 1 and 3, the foot rest 11 includes a horizontal platform 21 having an elevated foot-receiving pad 23 supported thereover by means of front and rear supports 25 and 27. The pad 23 is spaced above the platform 21 to form a compartment 29 which receives an upwardly opening pie-shaped tray 31 which has a tab 30 projecting forwardly thereof for securement to the platform 21 by means of a pivot screw 35 (FIG. 2). Thus, the rear extremity of the tray 31 is free to pivot to the opposite side of the pad 23 as shown in broken lines in FIG. 4 so the user thereof may have convenient access to tools placed in such tray.

Interposed between the back end of the tray 31 and the platform 21 is a friction lock in the form of a rubber

strip 39 (FIG. 2) which frictionally engages the underside of the free extremity of such tray 31 to frictionally hold such tray in its retracted position beneath the foot rest 23 as shown in solid lines in FIG. 4.

The leg 13 is in the form of a tube which is formed to define a closed square, and the upper extremity thereof is pivotally secured to the underside of the platform 21 by means of a pair of hinge brackets 41. A generally U-shaped strut, generally designated 43, is pivotally attached on its opposite ends to the sides of the leg 13 by means of pivot pins 45 and 47 and, in its supporting position, angles upwardly and rearwardly beneath the platform 21 to engage a pair of transversely spaced apart forwardly opening clips 49 affixed to the underside of such platform by means of screws 51. A latch element 53 (FIG. 3) is pivotally secured to the underside of the platform 21 intermediate to the clips 49 and is pivotable to project rearwardly beneath the strut 43 to hold such strut captive in the limit brackets 49.

Referring to FIGS. 3 and 5, the hook 15 is in the form of a tube which is bent back on itself and has the opposite extremities thereof bent to project inwardly toward one another to define axially aligned hinged elements which are retained in hinge brackets 55 that secure such hook to the underside of the platform 21.

Referring to FIG. 1, the opposite sides 57 and 59 of the hook 15 are spaced apart a distance greater than the width of the platform 21 so such sides will accommodate the width of such platform therebetween. The closed end of such hook 15 is bent sideways to project horizontally to form respective weight bearing portions 61 and 63 and is then again bent back on itself to form portions 65 and 67 which extend downwardly inside the rim of the bowl 19 to retain such hooks securely in position.

As shown in FIG. 3, the hook 15 can also act as a support leg and has the opposite extremities of a U-shaped brace, generally designated 71, affixed intermediately to the opposite sides thereof by means of pivot pins 73. When the hook 15 is in its supporting position, the brace 71 angles upwardly and forwardly to engage retaining clips 75 which open rearwardly to receive the closed end of such brace.

In operation, the foot stool of present invention may be taken from its folded condition shown in FIG. 2 and the leg 13 pivoted to its vertical position shown in FIG. 1 and the brace 43 rotated to angle upwardly and rearwardly to engage the limit clips 49 shown in FIG. 3. The retaining clip 53 may then be pivoted into position projecting under the leg 43 to retain it in its supporting position.

The brace 15 may then be rotated clockwise in the position shown in FIG. 2 and hooked over the edge of the toilet bowl 19. The user may then lower the lid of the toilet seat and may place, for example, his bare foot on the foot pad 23 for convenient access thereto in rendering himself a pedicure. During the process, the user may pivot the free extremity of the tray 31 about its pivot screw 35 to either side of the foot pad 23 as shown in broken lines in FIG. 4 so he may have convenient access to tools stored within such tray.

When the operator has finished his task, the tools may be returned to the tray 31 and such tray pivoted to its retaining cavity 29, it being realized that the rubber strip 39 acts to hold such tray frictionally in place beneath the foot pad 23 to cause such pad to act as a

cover to hold the tools captive in the tray during storage.

The stool may then be collapsed by releasing the retaining clip 53 and retracting the brace 43 from the limit brackets 49 to collapse the leg 13 upwardly 5 against the underside of the platform 21. The hook 15 may then be conveniently retracted by merely pivoting it counter-clockwise, as viewed in FIG. 1, about the right hand end of the platform 21 to the retracted position shown in FIG. 2. The entire unit may then be conveniently stored in a relatively compact area.

A particularly important feature of the stool of present invention is the capability of such stool being converted to an entirely ground supported stool as shown in FIG. 3. In this arrangement, the leg 13 is pivoted to the vertical position shown in FIG. 3 and the hook 15 is rotated 270° clockwise from the position shown in FIG. 2 to cause the support 63 to engage the ground or floor while the free end of the brace 71 is retained against the limit brackets 75 thus providing stable support for the stool during use.

From the foregoing it will be apparent that the collapsible foot stool of present invention provides a particularly convenient means for supporting one's foot while performing a pedicure or a shoe shining operation. By hooking the hook 15 over the edge of the toilet bowl 19 and lowering the lid thereon, the stool occupies very little space and is held in an extremely stable condition when the operator's weight is placed on the lid of the stool. Further, the stool may be utilized as a 30 more or less conventional foot stool as shown in FIG. 3 and may be collapsed to the relatively compact package shown in FIG. 2 for storage.

I claim:

1. A collapsible foot stool comprising: a foot rest formed with first and second extremities; a leg for supporting said first extremity; first pivot means attaching one end of said leg to said first extremity of said foot rest for pivoting of said leg between a retracting and a supporting position; a first brace pivotally connected on one end with the intermediate portion of said leg and engagable on its opposite end with the underside of said foot rest when said leg is in its supporting position; first limit means on the underside of said foot rest and engagable by said free end of said brace when said leg is in said supporting position and said brace is in its bracing position; a hanger projecting from said second extremity and formed on its projecting extremity with a turned back hook; second pivot means attaching the end of said hanger opposite said hook to said second extremity of said foot rest for pivoting thereof between a retracted position under said foot rest to a supporting position projecting upwardly from said foot rest whereby said leg and hook may be selectively pivoted to their retracted positions relative to said foot rest for storage of said stool and said leg and hook

may alternatively be pivoted to their supporting positions, the free extremity of said leg engaged with the floor to support said first extremity of said foot rest and the free extremity of said hook hooked over an edge of a support to support said second extremity.

2. A collapsible foot stool as set forth in claim 1 wherein:

said foot rest is formed with a tray-receiving compartment and includes a tray removably received in said compartment for receiving work tools.

3. A collapsible foot stool as set forth in claim 1 wherein:

said hanger is of the same length as said leg and is rotatable to a leg-support position, said foot stool further including:

second limit means for limiting rotation of said hook whereby said hook may be rotated to a supporting position to cooperate with said first leg in supporting said foot stool from the ground.

4. A collapsible foot stool as set forth in claim 1 that includes:

latch means carried from said foot rest and engageable with said brace for locking said leg in its supporting position.

5. A collapsible foot stool as set forth in claim 1 wherein:

said hanger includes rod means turned back on its self at its free end to form a closed end, having sides spaced apart a greater distance than the transverse width of said foot rest, said pivot means attaching said hanger to the underside of said foot rest whereby the free end of said hanger is free to pivot between the upper and lower sides of said foot rest;

said foot stool including second limit means for limiting rotation of said hanger to support said hanger in a position under said foot rest to cooperate with said leg to support said stool from the ground.

6. A collapsible foot stool as set forth in claim 2 that includes:

pivot means pivotally connecting one end of said tray to said foot rest.

7. A collapsible foot stool as set forth in claim 2 wherein:

said foot rest includes a foot pad disposed over said compartment and acting as a lid for retaining tools in said tray.

8. A collapsible foot stool as set forth in claim 2 that includes:

retaining means for normally retaining said tray in said compartment.

9. A collapsible foot stool as set forth in claim 1 wherein:

said second limit means includes a brace pivotally attached on one end of said hanger and engageable on its opposite end with the underside of said foot rest to support said brace in its bracing position.
